UNITED STATES PATENT OFFICE.

HERMAN ZERR, OF NEW YORK, N. Y.

REFRIGERATOR.

949,252.

Specification of Letters Patent. Patented Feb. 15, 1910.

Application filed April 28, 1906. Serial No. 314,115.

To all whom it may concern:

Be it known that I, HERMAN ZERR, a citizen of the United States, and a resident of the borough of Manhattan, city, county, and 5 State of New York, have invented certain new and useful Improvements in Refrigerators, of which the following is a specification.

My invention relates to refrigerators and 10 has for its object to provide a means for keeping the air therein at a uniform temperature and to minimize waste of the freezing medium.

Other objects of my invention will appear from the annexed description and the 15 features of novelty will be pointed out in the appended claims.

Reference is to be had to the accompanying drawing in which—

20 Figure 1 is a longitudinal section of a refrigerator with my improvements applied thereto; Fig. 2 is a section thereof on line 2—2 of Fig. 1, Fig. 3 is a section on the line 3—3 of Fig. 1, and Fig. 4 is a sectional 25 view of another form of receptacle.

A is the refrigerator, the walls and top and bottom of which may be of the usual construction and which is provided with the customary door A' for entrance and exit 30 therefrom. On each of the side walls of the refrigerator I have secured a shelf B held in position by braces C and provided with rollers D for the purpose to be described hereinafter. Each of these shelves B is pro- 35 vided with gutters E and E' running length- wise thereof and inclined toward the front of the refrigerator as shown in Fig. 1. Re- ceptacles F are arranged to be supported on the shelves B and to travel on the rollers D.

40 These receptacles F are guided on the said rollers D by the flange B' of the shelves B and the projection G on each of the side walls of the refrigerator. The receptacles are preferably made with corrugated sides 45 as shown and are adapted to contain a freezing mixture, as for instance a mixture of ice and rock salt. Each of the said receptacles F is provided with a removable cover F' having at each end projections F². Bolts F² 50 are pivoted at F⁶ to the receptacle and are provided with nuts adapted to engage the projections F⁵ to secure the cover in position. A gasket H of rubber or similar ma- terial is located between the said covers and

the upper edges of the receptacles so as to 55 insure a tight joint at these points when the covers are secured in position. Each recep- tacle F is provided with a drain cock F³ which extends over the gutter E so that as the freezing mixture melts the water will 60 run off from the receptacles into these gut- ters. Tubs or troughs I extend beneath the gutters E and E' at the lowest end thereof, which troughs receive any water which runs 65 into the gutters from the sides of the recep- tacles F or which runs from the said recep- tacles through the drain cocks F³ as the freezing mixture therein melts. These troughs I are suitably connected as by a tube I' with the sewer. 70

An opening J is arranged in the front wall of the refrigerator adjacent to each shelf B and is closed by a door J'. Thus when it is desired to replenish the freezing mixture in either of the receptacles F, the 75 door J is opened and the particular recep- tacle F is drawn through the opening J after which the cover F' is removed and a new supply of freezing mixture is intro- 80 duced into said receptacle. Each receptacle F is further provided at its rear end with a projection F⁴ which completely closes the opening J during this replenishing process. This arrangement prevents any warm outer 85 air from entering the interior of the re- frigerator during the refilling of the recep- tacles. The temperature of the refrigerator is thus maintained at a uniform point and waste of freezing mixture is done away with. The receptacles F are also practically 90 air tight when the covers F' are in position so that the freezing mixture contained therein melts very slowly and thus maintains its efficiency for a long time. By having the receptacles F arranged away from the side 95 walls of the refrigerator through the me- dium of the projection G and by providing the shelves B with openings B², the sides, ends and top and bottom of said receptacles all operate to abstract heat from the air in 100 the refrigerator. The rollers D serve to minimize the friction when the receptacles F are withdrawn from or replaced in the re- frigerator. A compartment K may be sup- 105 plied for the purpose of containing ice for other purposes than cooling of the air in the refrigerator, as, for instance, for cooling beverages etc. An opening L closed by a

door L' is provided for the purpose of communicating with the compartment K.

In the form of my invention shown in Fig. 4 I have provided the receptacle F with a dome like partition f which divides the said receptacle into two chambers f' and f''. The partition f is so constructed as to leave spaces f³ between a portion of it and the sides of the receptacle so that the freezing mixture contained in the chamber f' will practically surround said partition. The chamber f'' is adapted to contain game or other articles which are to be frozen, an opening f⁴ being provided for the purpose of introducing the game into said chamber f''. This opening f⁴ is normally closed by a door f⁵. The liquid, due to the melting of the freezing mixture is adapted to run from the receptacle into either of the gutters E or E' through a suitable drain-cock f⁶. In all other respects this form of receptacle may be the same as hereinbefore described.

By making the sides of the receptacle corrugated as shown, the area thereof is increased without necessitating a bulky or cumbersome construction.

While I have shown and described a refrigerator provided with two receptacles F, I desire it to be understood that in many cases one such receptacle will be sufficient; if desired, however, more than two such receptacles may be provided.

With my improvements I secure an even and effective temperature in the refrigerator with a minimum freezing medium, thus saving in the cost of ice, and I also economize in space, as my device does not take up nearly as much room as the ice compartment used at present, while rendering more efficient and satisfactory service.

Various modifications may be made with-

out departing from the nature of my invention as defined in the claims.

I claim:

1. A refrigerator comprising a box having an opening, an interior runway having its one end adjacent to said opening, troughs running lengthwise of said runway at opposite edges thereof, a longitudinal flange on said runway adjacent to one of said troughs, rollers journaled on said runway, a receptacle for a cooling agent provided with corrugated side walls, and adapted to travel on said rollers, said receptacle being arranged for projection through said opening and to be guided by said flange at a distance from the wall of the refrigerator and a removable cover for sealing the said receptacle. 45 50 55

2. A refrigerator comprising a box having an opening, an interior runway comprising spaced connected members and having its one end adjacent to said opening, troughs running lengthwise of said runway at opposite sides thereof, a longitudinal flange extending upwardly from said runway adjacent to one of said troughs, a projection on the side of wall of the refrigerator above said runway, a receptacle for a cooling agent arranged to travel on said runway between the projection and the flange and to be projected through said opening and means on said receptacle for closing said opening when the receptacle is fully projected. 60 65 70

In testimony whereof I have hereunto signed my name in the presence of two subscribing witnesses. 75

HERMAN ZERR.
